WITNESS:

G. F. Baker.

UNITED STATES PATENT OFFICE.

EDWARD D. STANSILL, OF SAPULPA, OKLAHOMA.

WRENCH.

1,404,665.

Specification of Letters Patent. Patented Jan. 24, 1922.

Application filed April 23, 1921. Serial No. 464,054.

To all whom it may concern:

Be it known that I, EDWARD D. STANSILL, a citizen of the United States, residing at Sapulpa, in the county of Creek and State 5 of Oklahoma, have invented new and useful Improvements in Wrenches, of which the following is a specification.

My present invention has reference to improvements in wrenches.

10 My object is to produce a wrench which shall be of a comparatively simple construction, easily operated for quick adjustment, firmly sustained in adjusted position to properly engage with an object between the 15 jaws thereof, and readily released from such engagement.

I accomplish the foregoing, and many other objects which will appear as the nature of the invention is better understood 20 by a construction, combination and operative association of parts, such as is disclosed by the drawings which accompany and which form part of this specification.

In the drawings:

25 Figure 1 is an elevation of a wrench constructed in accordance with this invention.

Figure 2 is a sectional view on the line 2—2 of Figure 1.

Referring now to the drawings in detail, 30 the numeral 1 designates the handle of my improved wrench. The handle has one of its ends widened outwardly from one of the edges thereof to provide a head 2. The head has its outer face channelled longitudinally and received in the said channel are the ears 3 formed on the inner face of a jaw 4. The jaw is of a width equalling that of the head and has its active face toothed or serrated. The jaw has its active face arranged at an inclination, and the ears thereof are engaged by pivots 5 which pass transversely through the head. The ear at the thickened end of the jaw has an elongated opening through which the pivot 5 passes, 45 and the numeral 6 indicates an arched spring which is received in the recess in the head 2 which contacts with the jaw to normally swing the same at an outward inclination with respect to said jaw.

50 On what may be termed the shank portion of the handle 1, that is the portion thereof to the rear of the head 2, there is arranged a yoke-like housing 7. The housing is preferably removably secured to the shank 55 by removable means 8. At the inner end of the housing the shank is provided with

spaced ears 8 and 9 respectively that extend beyond both of the edges of the said shank.

The movable jaw is indicated by the numeral 10 and is provided with an angle shank 60 11 formed with a toothed edge 12. The shank 11 passes through the housing 7 over one of the edges of the shank of the stationary jaw and is also guided between the ears 7. The shank 11 is formed with an upstanding lug 13 that is in the path of contact with the inner end of the housing 7, whereby the jaw 5 is limited in its outward movement with respect to the stationary jaw. On the edge of the shank of the stationary 70 jaw, that is the portion thereof which is indicated in the drawings by the numeral 14, opposite the toothed surface 12 of the shank 11, I secure one end of a flat spring 15. The opposite end of this spring is rounded upon 75 itself as at 16, and the said rounded portion contacts with the toothed edge 12 of the shank 11 canting or tilting the said shank and consequently bringing the jaw 10 at an inclination with respect to the jaw 4. 80

The shank 14, between the jaw and the spring 15 has its edge formed with a rounded depression 17, and one of the walls thereof has a transverse rounded slot 18 therethrough. The slot 18 provides a bearing 85 opening for the rounded head portion 19 of a dog 20. The dog is movable in the space between the toothed edge of the jaw 11 and the wall of the depression 17. The side walls of the housing 7, in a line with the dog 20 90 are depressed outwardly to provide for the free movement of links 21 which are disposed between the sides of the shank 14 and the side walls of the housing and which are pivoted, as at 22 to the dog 20. To the outer 95 end links 21 there is pivoted therebetween, as at 23, one end of the operating lever 24. The lever is arranged at an outward inclination from its pivotal connection with the links, and is provided with an enlarged or 100 thickened portion which is pivoted, as at 25, between the pairs of ears 9. The ears may be formed on the ends of plates 26, or both the plates and the ears may be integrally formed with the handle 1 and shank 14 of 105 the links. The plates 26 provide a pocket for the outer end of the handle whereby the said operating end of the handle cannot be accidentally contacted. The plates 26, near the said outer or operating end of the handle 110 24 are provided with arched depressions 27 forming a space whereby the finger of the

operator may be received and the lever depressed against the tension of a spring 28 which is disposed in a pocket 29 in the shank portion 14 of the handle 1 and which contacts with the inner surface of the lever.

It is believed that the construction, operation and advantages of the improvement will be obvious to those skilled in the art to which such inventions relate. A pressure on the 10 lever against the tension of the spring 28 will cause the latter to swing on its pivot 25 and draw on the links 21 to bring the dog 20 out of engagement with the teeth 12 of the shank 11. The other hand of the operator adjusts the jaw 10 with respect to the jaw 4. When an object is received between the jaws pressure on the lever is released and the object is turned by the swinging of the handle, 1. When an object is to be released from between the jaws, the lever is again operated to swing the dog out of engagement with the teeth 12. The spring 15 at all times causes the proper canting of the shank 11 to arrange the jaw 10 at the desired 20 inclination with respect to the jaw 4. The spring 28, which at all times exerts a pressure against the lever causes the latter to exert a pressure against the links 21 and consequently retain the dog 20 in engagement 25 with the teeth 12 regardless of the angular 30

arrangement of the link 11 with respect to the shank 14 or the stationary jaw 4.

Having described the invention, I claim:—

In a wrench, a handle having an extension providing a shank which terminates in a 35 head, a pivoted spring influenced jaw on the outer end of the head, a dog journaled on the shank inward of the head at one of the edges thereof, an arched spring secured to the said edge opposite the dog, a yoke-like 40 housing surrounding the shank and enclosing the dog and spring, spaced ears extending from the side edges of the shank at the inner end of the housing, links pivotally secured to the sides of the dog, a handle 45 member pivoted between one pair of the ears and pivotally connected to the links, a housing for the outer end of the lever including spaced plates projecting from the shank, spring means between the shank and lever 50 forcing the latter in one direction, a movable jaw having an angle toothed shank received through the housing, engaged by the first mentioned spring and having its teeth engaged by the dog, and a lug on the inner end 5 of the shank in the path of contact with the end of the housing.

In testimony whereof I affix my signature.

EDWARD D. STANSILL.
